H. A. SMITH,
CYLINDRICAL WALL STRUCTURE,
APPLICATION FILED AUG. 17, 1914.

1,250,685.

Patented Dec. 18, 1917.

UNITED STATES PATENT OFFICE.

HIRAM A. SMITH, OF PAW PAW, MICHIGAN.

CYLINDRICAL WALL STRUCTURE.

1,250,685.

Specification of Letters Patent. Patented Dec. 18, 1917.

Application filed August 17, 1914. Serial No. 857,132.

To all whom it may concern:

Be it known that I, HIRAM A. SMITH, a citizen of the United States, residing at Paw Paw, Michigan, have invented certain new and useful Improvements in Cylindrical Wall Structures, of which the following is a specification.

This invention relates to improvements in cylindrical wall structures.

10 In the building of cylindrical wall structures, such as silos, of blocks or staves of concrete or other material, where the blocks are of considerable size the blocks or staves are commonly disposed on end and it is customary to provide the structure with encircling hoops, the hoops being disposed at the joints when the blocks are laid in tiers without lapping the joints, so that the blocks are supported by the hoops at their ends only, 15 and when the blocks are laid to lap the hoops are disposed so as to cross the joints of part of the blocks and the centers of the remaining blocks, the result in either case is a tendency to break the blocks at the center 20 under the stresses to which they are subjected in adjusting themselves in the wall which, in addition to the resulting damage to the structure, is a source of danger.

It is the main object of my present invention to provide a cylindrical wall structure well adapted for silos and similar structures in which the wall blocks are so laid and supported by the hoops that the likelihood of the blocks breaking under the stresses to 35 which they are subjected in the wall is remote.

Further objects, and objects relating to structural details, will definitely appear from the detailed description to follow.

40 I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a front elevation of a silo embodying the features of my invention.

50 Fig. II is a detail horizontal section on a line corresponding to line 2—2 of Fig. I, the hoop being shown in full lines.

Fig. III is a detail vertical section on a line corresponding to line 3—3 of Fig. I.

55 Fig. IV is a detail view showing features of the door casing blocks 2.

Fig. V is an enlarged detail section on a line corresponding to line 5—5 of Fig. I, showing features of the wall blocks 3.

Fig. VI is a diagrammatic view illustrating a method which may be employed in the building of silos such as illustrated in Fig. I.

In the drawing similar reference characters refer to similar parts throughout the several views, and the sectional views are taken looking in the direction of the little arrows at the ends of the section lines.

Referring to the drawing, 1 represents a concrete foundation for the silo.

I provide door casing blocks 2 and wall blocks 3. The door casing blocks are somewhat thicker than the wall blocks, see Figs. II and IV, and are preferably somewhat wider. The door casing blocks are provided with tongues 4 on their facing edges, the tongues being located toward the front side of the blocks and adapted to receive the grooves 5 on the ends of the cross bars or door sill members 6. These door sill members are disposed at the joints of the door casing blocks with their ends lapping and abutting the edges of adjacent blocks. The door casing blocks are provided with sill engaging lugs 7 adjacent their ends so that the sill members 6 are properly located and the lugs assist in supporting the sills. The door casing blocks are rabbeted at 8 on their rear sides to provide stops for the doors 10. The door sill members are rabbeted at 11, to provide stops for the tops and bottoms of the doors. The doors are retained by the bars 12 engaging brackets 13. As the details of the door supporting means form no part of my present invention I do not illustrate or describe the same in further detail herein.

95 The wall blocks 3 are provided with tongues 14 and grooves 15 on their vertical edges, their ends being flat as shown in Fig. V.

The wall blocks are laid in courses, the blocks of the courses being staggered so as to interlap or break joints with the blocks of the adjacent courses. The blocks are laid so that their laps are substantial and uniform, lapping preferably one-third the length of the blocks, and in the structure illustrated the wall blocks are so laid. The length of the lap may, however, be considerably varied and practical results still be secured. The encircling hoops 16 are disposed about the courses and across the door sill members 6 and the door casing blocks.

The hoops are preferably disposed centrally between the opposite ends of the alternate staggered blocks of the courses. This locates the hoops between the longitudinal center of the block and one end and at substantial distances from its center and end and is the location preferred by me.

With this arrangement of the blocks in the courses and the location of the hoops, 10 the hoops embrace the blocks at a point well away from their ends so that the blocks effectively resist any crushing stress of the hoops and are not broken or dislocated by such stresses, and at the same time the blocks 15 are free to adjust themselves to a bearing at their vertical edges to withstand the stresses to which they are subjected in the wall and the stresses of the hoops. The interlapping long and short ends of the 20 blocks, that is, relatively long and short to the position of the hoops thereon, coact to provide a perfect balance, so that, as has been demonstrated in practice, they readily accommodate themselves to stresses and 25 strains, and the likelihood of the blocks breaking under strains and stresses in the wall is very remote, as has been demonstrated in the erection of silos by practical experience.

30 While I prefer to lay the blocks with the one-third and two-thirds laps as illustrated, this can be considerably varied and quite satisfactory results be secured if the lap is substantially unequal and the hoops 35 placed so as to cross each wall block between one end and the center thereof and at a substantial distance from its end and center.

While I prefer to form the blocks with 40 flat abutting ends quite satisfactory structures will result if the ends are tongued and grooved together the same as the sides as it is found that the blocks will still adjust themselves to a considerable extent in the wall to compensate for irregularities in the 45 blocks and the stresses arising from hooping and the vibration of the structure from wind or other causes.

In starting a wall, such as in the structure illustrated, where the length of the average 50 block is thirty inches, I provide door casing starting blocks 2' ten inches in length and wall starting blocks 3' twenty inches in length. These are laid as shown in the diagram in Fig. VI. A suitable filler 17 being used at the bottom of the door opening, there being as many fillers used as desired.

The blocks 3' are also used in the top tier or finishing tier. Where the lugs 7 interfere with the laying of the filler blocks 17 60 the lugs are chiseled out. The casing blocks are grooved on both sides of the lugs 7 to

receive the tongues of the filler blocks where several are used.

I have illustrated and described my improvements embodied in a silo, but it will 65 be readily understood that certain features thereof can be readily adapted for other circular wall structures, such as water tanks, stand pipes, grain bins, cribs and the like, and while I have referred to the blocks as 70 being concrete blocks it will be understood that any suitable material may be employed.

Having thus described my invention, what I claim as new and desire to secure by Letters Patent, is:

75 1. A cylindrical wall structure of the class described, comprising door casing blocks disposed on end, door sill members disposed at the door casing block joints with their ends abutting the edges of adjacent 80 door casing blocks, wall blocks laid in courses, the blocks being staggered in the courses and breaking joints with those of adjacent courses, said wall blocks having coacting tongues and grooves on their vertical edges and flat abutting end joints, the lap of said blocks being substantially one-third their length, and hoops disposed about the courses centrally between opposite ends of alternate blocks thereof and across the 90 door sills, all coacting for the purpose specified.

2. A cylindrical wall structure of the class described, comprising wall blocks laid in courses with the blocks staggered in the 95 courses and breaking joints with those of adjacent courses, the lap of the blocks being substantially one-third their length, and hoops disposed about the courses centrally between the opposite ends of the alternate 100 blocks thereof so that the blocks have alternately long and short ends relative to the hoops and coact with the blocks of adjacent courses in balancing and adjusting to stresses.

105 3. A cylindrical wall structure of the class described, comprising wall blocks laid in courses with the blocks staggered in the courses and breaking joints with those of adjacent courses, the lap of the blocks being substantially one-third their length, and hoops disposed about the courses centrally between the opposite ends of the staggered blocks thereof.

110 In witness whereof, I have hereunto set my hand and seal in the presence of two witnesses.

HIRAM A. SMITH. [L.S.]
